UNITED STATES PATENT OFFICE.

CHARLIE CAMDON FETTY, OF ELDORADO, KANSAS.

COUNTERBALANCING MEANS FOR WELL-PUMPING APPARATUS.

Application filed May 20, 1926. Serial No. 110,581.

My invention relates to counterbalancing means for well pumping apparatus and more particularly to means for counterbalancing the action of the weight of the pumping 5 means on the band wheel shaft.

It is a purpose of my invention to provide a counterbalancing weight on the band wheel shaft for counteracting the action on said shaft of the weight of the pumping means, 10 that is, the pump rods and all the other apparatus carried by the opposite end of the walking beam to that connected with the band wheel. The weight of the pumping apparatus is exerted at one end of the walking beam and this causes the opposite end 15 of the walking beam to have a normal tendency to move upward, which action is transferred to the crank carried by the band wheel shaft for actuating the walking beam through the pitman connecting the walking beam and said crank. This causes an unbalanced condition of the band wheel shaft, 20 the weight of the drilling apparatus acting to retard the rotation of the band wheel shaft through one half of its movement and acting to aid the rotation thereof through the other half of its movement. In order to overcome this unbalanced condition my improved balancing means has been provided 25 on the band wheel shaft.

My improved balancing means or counterbalancing device comprises a yoke-like arm that is secured to the band wheel shaft to rotate therewith, which is provided with a 30 weight at the outer end thereof. As the weight of the pumping apparatus varies due to the variation in the length of the pump rod and variation in the size of the pump rod, means is provided for adjusting for this 35 variation in weight by providing detachable counterbalancing weights carried by the yoke-like arm. By providing the counterbalancing weight on the band wheel shaft the weight otherwise placed on the walking beam for counterbalancing purposes is 40 avoided, thus preventing any unnecessary strain on the walking beam and its support.

Other objects and advantages of the invention will appear as the description of the 45 accompanying drawings proceeds. However, I desire to have it distinctly understood that I do not intend to limit myself to the exact details shown or described, but that I intend to include as part of my invention all such obvious changes and modifications of parts as would occur to a per-

son skilled in this art and as would fall within the scope of the claims.

In the drawings:

Fig. 1 is a perspective view of a well 60 pumping apparatus showing my improved counterweight applied to the band wheel thereof:

Fig. 2 is a transverse sectional view of the band wheel, showing my improved counterweight mounted on the band wheel shaft. 65

Fig. 3 is a perspective view of the counterweight member with the cap portion thereof separated therefrom.

Fig. 4 is a perspective view of one of the 70 adjusting weights, and

Fig. 5 is a sectional view through the counterweight and the adjusting weight, showing the inter-engaging ribs and grooves on said members. 75

Referring in detail to the drawings:

My improved counterbalancing means is shown as being applied to a well pumping apparatus comprising a walking beam 10 upon one end of which is mounted suitable 80 well pumping means 11, the other end of the walking beam having the pitman 12 mounted thereon by means of the stirrup 13, the opposite end of said pitman being connected with the crank 14 carried by the 85 shaft 15. Said shaft 15 has the band wheel 16 keyed thereto so that said band wheel and shaft rotate together, the shaft being driven through the band wheel 16. The shaft is mounted upon suitable bearing members 17 which are supported upon the sills 18 in any desired manner, the shaft 15 extending beyond one of the bearing members 17 and carrying on said extension thereof a counterbalancing member 19. Said counterbalancing member is provided with a shaft engaging portion 20 which is provided with suitable openings in the cap 22 for securing said cap thereto by means of the securing members 23. The counterbalancing 100 member 19 is secured to the shaft 15 to rotate therewith, by means of the key 24 engaging said shaft and the cap 22, a set screw 23 holding said key in place. The set screw may be released, the screws 23 loosened and 105 the key removed to permit the shaft 15 to turn in the member 19 when removing or replacing the pump rod.

The counterbalancing member 19 is further provided with a pair of diverging arms 110 25 which are connected by means of the cross member 26 at their outer ends, said cross

member 26 being made extremely thick and heavy to serve as a counterbalancing weight. The arms 25 and cross member 26 thus form a yoke-like arm having an opening therein within which a suitable adjusting weight is adapted to seat against the flat seat 28 provided on the inner face of the transversely extending portion 26, and is provided with ribs 29 which are adapted to engage in the grooves 30 provided on the inner face of one of the arms 25. The detachable weight 27 is moved into position across the face 28 toward the grooves 30 in the arm 25 with the ribs 29 in engagement with the grooves. Bolts 31 or other suitable securing members are then engaged with the openings 32 in the cross piece 26 and openings 34 in the weight 27 to hold the weight 27 in position. Any number of such weights 27 may be inserted within the yoke-like arm 19 in engagement with the grooves 30, the bolts or securing members 31 being provided of suitable length for holding the weights 27 on the yoke-like arm.

25 It will be noted that the yoke-like arm 19 is substantially aligned with the crank 14. Accordingly the upward pull of the pitman 12 due to the weight of the pumping means will be counteracted by the downward pull of the weight 26 and adjusting weights 27, so that a substantially balanced condition of the shaft 15 will exist, which will provide a substantially smooth rotation of the band wheel 16 due to the fact that the load thereon is substantially the same at all times.

What I claim and desire to secure by Letters Patent is:

1. In pumping apparatus, a shaft, a band wheel thereon, a crank on said shaft and a counterbalancing member on said shaft, said counterbalancing member comprising a yoke-

like arm having a shaft engaging portion at one end thereof and a weight removably anchored in said yoke-like arm.

2. In pumping apparatus, a shaft, a band wheel thereon, a crank on said shaft and a counterbalancing member on said shaft, said counterbalancing member comprising a yoke-like arm having a shaft engaging portion at one end thereof and a weight at the other end thereof, said yoke-like arm having a seat thereon for receiving adjusting weights and means on said arm engageable by said weights to hold said weights from lateral movement off said arm.

3. In pumping apparatus, a shaft, a band wheel thereon, a crank on said shaft and a counterbalancing member on said shaft, said counterbalancing member comprising a yoke-like arm having a shaft engaging portion at one end thereof, a weight removably located in said yoke-like arm, and means for releasing said weighted member from said shaft so that said shaft may rotate relative thereto.

4. In pumping apparatus, a shaft, a band wheel on the shaft, a crank on the shaft and a counterbalance on the shaft comprising a weighted member having a seating recess and keyways, and a weight removably seated in said recess and having keys projected into said keyways.

5. In pumping apparatus, a shaft, a band wheel on the shaft, a crank on the shaft and a counterbalance on the shaft comprising a weighted member having a seating recess and keyways, a weight removably seated in said recess and having keys projected into said keyways to retain the weight against lateral displacement, and bolts extending through the weighted member and weight.

In testimony whereof I affix my signature.

CHARLIE CAMDON FETTY.
